OUTDOOR CASH BOX-IMPRINTER HOOD

Raymond B. Dawley, 920 Stony Hill Road, and Chester
L. Joyce, 1226 Fernside St., both of Redwood City,
Calif. 94061

Filed Mar. 17, 1971, Ser. No. 125,456

Term of patent 14 years

Int. Cl. D31

U.S. Cl. D52—4 A

FIG. 1 is a top, front and left side perspective view of an outdoor cash box-imprinter hood showing our new design;

FIG. 2 is a right side elevational view thereof;

FIG. 3 is a front elevational view thereof, having showings of a cash box and imprinter illustrated in broken lines for environmental purposes only;

FIG. 4 is a top plan view thereof;

FIG. 5 is a rear elevational view thereof; and

FIG. 6 is a bottom plan view thereof.

We claim:

The ornamental design for an outdoor cash box-imprinter hood as shown.
